US0D1062513S

(12) **United States Design Patent** (10) Patent No.: **US D1,062,513 S**
(45) Date of Patent: ** Feb. 18, 2025

(54) **EARRING**

(71) Applicant: **Jianguo Lyu**, Zhejiang (CN)
(72) Inventor: **Jianguo Lyu**, Zhejiang (CN)
(**) Term: **15 Years**
(21) Appl. No.: **29/962,736**
(22) Filed: **Sep. 12, 2024**
(51) LOC (15) Cl. **11-01**
(52) U.S. Cl.
USPC **D11/40**

(58) **Field of Classification Search**
